UNITED STATES PATENT OFFICE.

PICKETTE M. CALLAHAN, OF DENVER, COLORADO.

COMBINED RULE AND SQUARE.

SPECIFICATION forming part of Letters Patent No. 715,194, dated December 2, 1902.

Application filed July 31, 1902. Serial No. 117,870. (No model.)

To all whom it may concern:

Be it known that I, PICKETTE M. CALLAHAN, a citizen of the United States of America, residing at Denver, in the county of Arapahoe 5 and State of Colorado, have invented certain new and useful Improvements in a Combined Rule and Square; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in a combined carpenter's rule and square; and it consists in changing the ordinary rule so that it shall be adapted for use as a carpenter's square and also for measuring angles.

20 In the ordinary construction of carpenter's rule the hinge parts project into the angle formed by the two arms of the instrument. My improvement consists in cutting away these parts, so that when the arms are at right 25 angles to each other or stand at any angle between ninety degrees and zero the hinge parts do not protrude into the interior angle, thus allowing the rule to fit the exterior angle of any body. In order to hold the two hinge 30 parts together, one of them is provided with a curved slot through which a pin fast in the other part is passed. This construction prevents the central hinge-pin attached to one hinge part from slipping out of the opening 35 formed in the side of the perforation in the other hinge part. This opening in the side of the perforation is formed by cutting away the hinge parts, as aforesaid.

Having briefly outlined my improved construction, I will proceed to describe the same in detail, reference being made to the accompanying drawings, in which is illustrated an embodiment thereof.

40 In the drawings, Figure 1 is a fragmentary view of a carpenter's rule provided with my improvements and shown in the closed position. Fig. 2 shows the same construction with the rule-arms extending at right angles to each other. Fig. 3 illustrates the same 45 with the arms forming an angle of forty-five degrees. Figs. 4 and 5 are detail edge views

of the two members. Figs. 6 and 7 are plan views in detail of the same.

The same reference characters indicate the same parts in all the views.

Let the numerals 5 and 6, respectively, designate the two rule arms or members, which are provided with hinge parts 7 and 8, respectively. The part 8 is double or bifurcated and provided with a pin 9, which fits a recess 10, formed in the part 7, which is straddled by the part 8. As compared with the ordinary construction of rule one-fourth of each hinge part is cut away, as shown at 12 and 13, so that when the two rule members 60 stand at right angles to each other, as shown in Fig. 2, or at a less angle, as shown in Fig. 3, the hinge parts do not protrude into the angle. Hence this construction makes the rule fit any exterior angle between ninety degrees and zero. By cutting out the hinge parts, as shown at 12, the perforation 10 is opened on one side, which would allow the pin 9 to slip out, thus disconnecting the two rule parts. To prevent this result, the hinge 70 part 7 is provided with a curved slot 14, through which a pin 15, fast in the part 8, passes and in which the said pin travels during the operation of opening and closing the rule members. The slot 14 is bounded by 80 arcs struck from the hinge center of the rule. The slot 14 is of sufficient length to allow the rule members the ordinary or necessary range of movement.

In Fig. 2 is illustrated the manner of applying the rule to a square body, which is illustrated by dotted lines and designated 16. The dimensions of the body are easily found in this manner. The manner of measuring a cylindrical body 17 is also illustrated in Fig. 90 2. The diameter of the body 17 may be observed with reasonable accuracy by glancing from the tangential points 18 and 19 to the points 20 and 21 of the rule.

The member 5 of the rule is graduated and 95 marked to indicate degrees, as shown at 22, adjacent the curved shoulders 23, which the part 8 of the hinge engages. This graduation is for measuring and marking angles.

From the foregoing description it will be 100 understood that my improved instrument, while capable of use for all purposes as a car-

penter's rule, may also be employed to perform the functions of a square and calipers.

Having thus described my invention, what I claim is—

- 5 1. A rule composed of two hinged members, one having a perforation and the other a hinge-pin to engage said perforation, the hinged parts being cut away on the closing side of the rule to open the hinge-pin perforation, a portion of the hinge-pin being also cut away, the parts being arranged to allow the pin to slip into and out of the pin-perforation freely, one of the hinged parts having a curved slot, and the other hinged part being 10 provided with a pin passing through said slot, to retain the two parts in place when assembled.
- 15 2. A rule composed of two hinged members, one having a perforation and the other a

hinge-pin to engage said perforation, the 20 hinged parts being cut away on the closing side of the rule to open the hinge-pin perforation, a portion of the hinge-pin being also cut away, the parts being arranged to allow the pin to slip into and out of the pin-perforation freely, one of the hinged parts having a curved slot, and the other hinged part being 25 provided with a pin passing through said slot, to retain the two parts in place when assembled, one of the rule members being graduated and properly marked to measure angles, substantially as described.

In testimony whereof I affix my signature in presence of two witnesses.

PICKETTE M. CALLAHAN.
